UNITED STATES PATENT OFFICE.

THOMAS J. MALONEY, OF YOUNGSTOWN, OHIO.

BUNDLING TABLE.

Application filed July 12, 1923. Serial No. 651,076.

To all whom it may concern:

Be it known that I, THOMAS J. MALONEY, a citizen of the United States, and a resident of Youngstown, county of Mahoning, and 5 State of Ohio, have invented a new and useful Improvement in Bundling Tables, of which the following is a specification, the principle of the invention being herein explained and the best mode in which I have 10 contemplated applying that principle, so as to distinguish it from other inventions.

The present improvements relate more particularly to tables such as are used for measuring and bundling small iron pipes and 15 like articles, but it will be of course understood that no limitation to any such particular use is implied. According to the current practice, the pipes after being measured are dropped onto stationary hooks disposed 20 along one side of a table and when such hooks contain the proper number of pipes, the latter are tied into a bundle and the bundle lifted onto a truck. The transfer, however, of such bundle to the truck is ex- 25 tremely awkward and wasteful of time inasmuch as three men usually are employed to tie the bundles and each time a bundle is transferred, the men have to step over the bundle or otherwise get out of its way.

30 The object of the present invention accordingly is to provide, in conjunction with a bundling table, movable hooklike supporting members which will normally retain the desired number of pipes or like articles as 35 they are assembled but which may upon the bundle being tied be moved out of the way and allow such bundle to be deposited onto a truck or equivalent transporting device without requiring any change in position of 40 the operatives working at the table.

To the accomplishment of the foregoing and related ends, the invention, then, consists of the means hereinafter fully described and particularly pointed out in the claims, 45 the annexed drawings and the following description setting forth in detail certain mechanism embodying the invention, such disclosed means constituting, however, but one of various mechanical forms in which 50 the principle of the invention may be used.

In said annexed drawings:—

Fig. 1 is a plan view of a bundling table embodying my present improvements; Fig. 2 is a front elevation thereof; and Fig. 3 55 is an end elevation viewing the table from the left in Figs. 1 and 2.

The table 1 proper is of narrow elongated form, the length being determined of course by the length of the pipes or other articles which it is desired to handle thereon. Ad- 60 jacent its one end, the left as shown, the table is provided with an abutment 1^a against which the ends of the pipes may be brought in order to measure the same and an intermediate section 1^b of the table is prefer- 65 ably removable to afford convenient access to the space beneath when desired. Associated with the table is a series of trans- 70 versely extending guides 2 mounted on posts 3 which serve at the same time to support 70 the table, the latter together with such guides 2 being carried by transverse bars 4 secured to the upper ends of said posts. It will be noted that the guides incline down- 75 wardly towards the table in order to facilitate the movement of the pipes onto the latter after they have been lifted from the skips 5 onto said guides and that the table 1 overlies a trackway 6 at a sufficient elevation to permit the passage along said track- 80 way of a truck 7 to which the pipes after being bundled are ultimately to be delivered.

For the use of the workmen a raised platform 10 is provided alongside of said track- 85 way 6, such platform affording convenient 90 access to the table at any point thereof. Located at suitable intervals along the same side of the track as platform 10 are other posts 11 which rise through and above the platform to approximately the same height 90 as table 1. Each such post carries at its upper end a stop member 12 wherewith a hook member 13, pivotally mounted at an adjacent point in the table, is adapted to contact. The series of posts 11 and hooks 95 13 are preferably equidistantly spaced lengthwise of the table and the distance be- 100 tween the stop members 12 and the edge of the table is sufficient to allow a bundle of the desired size to pass therethrough when the hooks are mounted out of the way. The hooks are all mounted on a longitudinally 105 extending shaft 14 that is provided with a counterweighted arm 15 normally serving to maintain their hooks in closed position, i. e. in contact with stops 12. By means, however, of an upstanding handle 16 on one end of said shaft, said hooks may be swung to the left, i. e. in a clockwise direction, so as to leave clear the space between 110 the edge of the table and the stops 12. An arm 17 projects downwardly and inwardly

from each post 12 so as to guide a bundle received thereon over the adjacent side of truck 7, as clearly shown in Fig. 3. From the foregoing description of the construction and operation of the several component parts of my improved bundling table it is believed the operation of the latter as a whole will be readily understood. The pipes as received on the table 1 are measured and collected into bundles in the pocket that is in effect provided by the series of hooks 13 when the latter are, as is normally the case, held in contact with stops 12 by means of counterweight 15. When the proper number has been thus collected, they are tied into a bundle and the hooks then tipped by suitably swinging lever 16, whereupon the bundle is discharged from the aforesaid pocket and allowed to slide down the inclined guides 17 onto the truck. It will not only be obvious that the workmen on platform 10 will not have to move out of the way in order that the bundle may be thus discharged, but that the labor of measuring and assembling the pipes into bundles is in other respects greatly lessened and the speed with which the bundling can be carried out correspondingly increased.

It will be understood of course that various means other than the specific arrangement of counterweighted lever 15 and hand lever 16 may be employed for operating the hooks 13; also that a conveyor either of the roller or belt type may be substituted for the truck 7 as the means for removing the bundle when discharged from the bundling table.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. The combination of a table, and a series of members projecting horizontally beyond one edge thereof to form a pocket wherein articles from said table may be assembled, said members being transversely movable to drop such assembled articles when desired.

2. The combination of a table, and a series of members pivotally attached to one edge of said table and projecting horizontally therefrom and forming a pocket wherein articles from said table may be assembled, said members being transversely movable to drop such assembled articles when desired.

3. The combination of a table, a series of members pivotally attached to one edge of said table and forming a pocket wherein articles from said table may be assembled, said members being transversely movable to drop

such assembled articles when desired, and guides arranged to direct such assembled articles beneath said table, when thus dropped.

4. The combination of a table, a conveyor beneath said table and longitudinally movable thereof, a series of members attached to one edge of said table and forming a pocket wherein articles from said table may be assembled, said members being transversely movable to drop such assembled articles when desired, and guides arranged to direct such assembled articles onto said conveyor beneath said table, when thus dropped.

5. The combination of a table, a series of supports disposed alongside of but spaced from one edge of said table, and members adapted to bridge the space between such table edge and said supports, said members normally forming a pocket wherein articles from said table may be assembled and being transversely movable to clear such space and drop such assembled articles.

6. The combination of a table, a series of supports disposed alongside of but spaced from one edge of said table, and a corresponding series of members pivotally attached to said table and adapted to bridge the space between such table edge and said supports, said members normally forming a pocket wherein articles from said table may be assembled and being transversely movable to clear such space and drop such assembled articles.

7. The combination of a table, a conveyor beneath said table and longitudinally movable thereof, a series of supports disposed alongside of but spaced from one edge of said table, a corresponding series of hook-like members pivotally attached to said table and adapted to bridge the space between such table edge and said supports, said members normally forming a pocket wherein articles from said table may be assembled and being transversely movable to clear such space and drop such assembled articles, and downwardly and inwardly inclining guides on said supports arranged to direct such assembled articles onto said conveyor.

8. The combination of a table, a conveyor beneath said table and longitudinally movable thereof, a series of supports disposed alongside of but spaced from one edge of said table, an oscillatory shaft extending longitudinally of such table edge, a series of hook-like members carried by said shaft opposite said supports respectively, stops on said supports adapted to be engaged by said members and forming therewith a pocket wherein articles from said table may be assembled, and means connected with said shaft normally maintaining said members in contact with said stops.

9. The combination of a table, a conveyor beneath said table and longitudinally movable

- thereof, a series of supports disposed alongside of but spaced from one edge of said table, an oscillatory shaft extending longitudinally of such table edge, a series of hook-like members carried by said shaft opposite said supports respectively, stops on said supports adapted to be engaged by said members, and forming therewith a pocket wherein articles from said table may be assembled, and a counter-weight connected with said shaft normally maintaining said members in contact with said stops.
10. The combination of a table, a conveyor beneath said table and longitudinally movable thereof, a series of supports disposed alongside of but spaced from one edge
- of said table, an oscillatory shaft extending longitudinally of such table edge, a series of hook-like members carried by said shaft opposite said supports respectively, stops on 20 said supports adapted to be engaged by said members, and forming therewith a pocket wherein articles from said table may be assembled, means connected with said shaft normally maintaining said members in contact with said stops, and downwardly and inwardly inclining guides on said supports arranged to direct such assembled articles onto said conveyor.
15. Signed by me, this 9th day of July, 1923.

THOS. J. MALONEY.
